7 Claims. (Cl. 134—95)

This invention relates generally to the art of cleaning and washing houseware such as dishes and more particularly relates to improved methods and apparatus for cleaning dishes.

It is an object of the present invention to provide a washing system capable of washing all surfaces of household ware, primarily by direct impingement of fluid jets, not dependent on deflected or run-off water for some surfaces of the ware.

Another object of the present invention is to provide a drying system which dries the houseware at cooler temperatures than heretofore available and without requiring that the air used for drying be taken from or delivered to the living area or room in which the drying system is located.

Another object of the present invention is to provide dishwashing apparatus which eliminates the necessity of initially conditioning the dishes for treatment in the machine by scraping or by manual prewashing.

Yet another object of the present invention is to provide dishwashing apparatus which is easier to load.

A still further object of the present invention is to provide an improved method of distributing liquid throughout the treatment zone of a dishwasher to obtain improved liquid distribution to all surfaces of ware racked in the machine.

Another object of the present invention is to provide liquid distributing means which will impinge jets of liquid against ware racked in the machine from opposite directions.

Another object of the present invention is to provide a form of a dishwashing machine wherein reaction spray arms are simultaneously rotated and pivotally oscillated thereby to produce a changing pattern of liquid distribution.

Yet another object of the present invention is to provide an improved form of dish rack.

Many other features, advantages and additional objects of the present invention will become manifest to those versed in the art upon making reference to the detailed description which follows and the accompanying sheets of drawings in which a preferred structural embodiment of a dishwashing apparatus capable of carrying out the methods herein disclosed is shown by way of illustrative example.

On the drawings:

Figure 1 is a front elevation of a dishwasher according to the present invention combined with a kitchen sink, parts of the apparatus having been removed for the sake of clarity of disclosure and parts being shown in cross-section;

Figure 2 is an end elevational view showing additional details of construction of the dishwashing apparatus of the present invention and illustrating parts of the structure in cross-section as viewed on line II—II of Figure 1;

Figure 3 is a fragmentary rear elevational view with parts broken away and with parts shown in cross-section illustrating additional details of construction of the drying system of the present invention;

2

Figure 4 is a fragmentary cross-sectional view taken substantially on line IV—IV of Figure 1;

Figure 5 is a view generally similar to Figure 1 but showing an alternative form of rack structure and showing another embodiment of dishwasher incorporating the principles of the present invention;

Figure 6 is a somewhat diagrammatic view of a dishwasher incorporating the principles of the present invention and showing specifically means for simultaneously 10 rotating and pivotally oscillating a reaction spray arm mechanism;

Figure 7 is a cross-sectional view of the oscillating mechanism shown in Figure 6;

Figure 8 is a plan view of the reaction spray arms of 15 Figure 5;

Figure 9 is an elevational view with parts removed showing a two-way valve arrangement for the dishwasher of the present invention;

Figure 10 is a top plan view of the dish rack embodied in the view of Figure 5;

Figure 11 is a cross-sectional view taken generally on 20 line XI—XI of Figure 8; and

Figure 12 is a cross-sectional view taken generally on line XII—XII of Figure 8.

As shown on the drawings:

The dishwashing methods and apparatus disclosed herein are suitable for application in the form of different models such as built-in dishwashers, free standing dishwashers or portable dishwashers, however, for purposes 30 of illustrating the principles of the present invention, the dishwashing apparatus is disclosed in combination with a sink cabinet 10 having a splashboard 11 and a counter top 12 adjacent a sink tub 13 draining into a waste disposal unit 14 connected by means of a suitable drain conduit 16 having therein a trap 17 to a drain outlet 18. The sink is supplied with hot and cold running water through a faucet 19, the discharge of which is controlled by a hot water valve 20 and a cold water valve 21. It will be understood that the valves 20 and 21 control 35 the supply of water from the usual domestic supply.

Mounted inside of the sink cabinet 10 and underneath the counter top 12 is a dishwasher indicated generally by the reference numeral 22. The dishwasher 22 comprises a housing or casing 23 forming a generally rectangular washing compartment or treatment zone indicated generally by the reference numeral 24. More specifically, the casing 23 includes side walls 26, 26, a top wall 27, a rear wall 28 and a front opening 29 which is adapted to register with a suitable open area provided in the sink cabinet 10 in the front wall thereof.

A door 30 is provided to close the opening 29, thereby to provide a front wall for the washing compartment or treatment zone 24. A hinge connection indicated at 31 and including a hinge pin 32 fastens the door 30 along the lower edge thereof to the casing 23 of the dishwasher 22. The door 30 moves from a fully closed position into a generally horizontally disposed open position, the open position of the door 30 being clearly illustrated in Figure 2 of the drawing.

Each of the end walls 26, 26 of the casing 23 is provided with a track member 33, the tracks 33, 33 lying in opposed coplanar relation and facing inwardly of the washing compartment or treatment zone 24 to provide a guide means for movably supporting a large, single level basket-type dish rack indicated at 34.

The dish rack 34 has a plurality of rollers 36 which engage the respective track members 33, 33. Additionally, the dish rack 34 has one or more sets of wheels or rollers 37 engaging a trackway surface 38 formed on opposite ends of the inner wall surface 39 of the door 30. The spacing relationship between the trackway surfaces 38, 39 and the track members 33, 33 as well as the spacing

relationships between the wheels or rollers 36 and 37 are such that the dish rack 34 will be fully supported whenever it is moved out of the washing compartment or treatment zone 24 and into an accessible loading position as shown in Figure 2. Because the dish rack 34 has only a single level, all ware may be conveniently placed therein without stacking. The trackway surfaces 38 terminate in stop portions 40 which prevent overtravel of the dish rack 34 with respect to the door 30.

The casing 23 has a bottom wall member 41 which forms the bottom of the washing compartment or treatment zone 24. Additionally, there is provided a bottom wall member 42 forming the bottom of a sump 43 which operates as a tub sump for the dishwasher 22. The sump 43 preferably includes an immersion-type heater 44 for imparting thermal energy to the liquid solutions which accumulate in the sump 43.

The sump 43 provides a supply for a chamber 46 leading to a combination drain pump and disposal unit 47 driven by a motor 48 through a pulley belt 49.

The pump-disposal unit 47 reduces any solid waste which may be rinsed from the dishes and pumps such material together with soiled liquid out of the dishwasher through a waste pipe conduit 50 communicating with the conduit 16 leading to the outlet 18.

The chamber 46 has an outlet 51 which is screened as at 52 and which communicates with the eye of a centrifugal pump 53 by means of a conduit connection 54.

The pump 53 is driven by the motor 56 and liquid discharged by the pump 53 is delivered to an outlet conduit 57 having branch conduits indicated at 58, 59 and 60, respectively.

The branch conduit 58 is controlled by an electrically operated control valve 61 and delivers fluid to a rotatable reaction spray arm 62 having a plurality of longitudinally spaced nozzles 63 arranged to direct jets of fluid generally upwardly through the washing compartment or treatment zone 24. Additionally, at the ends of the reaction spray arm 62 there are provided angularly inclined spray nozzles 64, thereby enlarging the scope of coverage in the jet pattern developed by the reaction spray arm 62. The reaction spray arm 62 gives a hard-hitting full coverage spray over all ware in the dish rack 34 as the reaction spray arm 62 rotates by reaction of the jets emanating from the nozzles 63 and 64.

The conduit 59 is controlled by an electrically operated valve 66 and conducts fluid to a rotatable reaction spray arm 67 having a plurality of longitudinally spaced nozzles 68 and angularly inclined end nozzles 69. It will be understood that the nozzles 68 and 69 are suitably inclined so that the reaction spray arm 67 will be rotated upon forcing fluid under pressure out of the nozzles 68 and 69.

It will be further noted upon referring to Figure 1 that the reaction spray arms 62 and 67 are in overlapping relation. Thus, most of the washing compartment or treatment zone 24 receives double coverage if both of the arms 62 and 67 are simultaneously rotated.

The conduit 60 is controlled by an electrically operated valve 70. The liquid flow through the conduit 60 is divided into two separate branch ducts 71 and 72 (Figure 2), the duct 71 leading to a manifold 73 extending across the front portion of the machine between the end walls 26, 26, and the duct 72 leading to a manifold 74 extending across the rear portion of the machine between the end walls 26, 26.

Along the entire length of each manifold 73 and 74, there are provided longitudinally spaced nozzles 76 which direct jets of fluid generally downwardly towards the opposite corner of the washing compartment or treatment zone 24. A typical arrangement is indicated in detail in Figure 4 wherein the jet is shown emanating from the upper right-hand corner of the washing compartment (using the orientation of Figure 2) down towards the lower left-hand corner of the washing compartment.

In order to avoid interference with the door 30, the top wall 27 of the casing 23 may be relieved or offset as at 77 to accommodate the manifold 73.

5 In order to charge the washing compartment or treatment zone with a supply of washing solution or liquid for washing and rinsing the ware placed therein, an improved dispensing and mixing system is employed which is characterized by a mechanism operable by a single valve actuator to dispense a measured amount of additive material such as a detergent while closing the system against flow, and thereafter, closing the reservoir of additive material and opening the system to flow of additive material and primary material, such as water, whereby the materials are mixed.

10 15 For example, as shown in Figure 2, a supply of detergent is carried in a reservoir 78 and is discharged to an outlet 79 communicating with the interior of the washing compartment or treatment zone 24. The dispensing and mixing mechanism which controls the regulation of the 20 discharge of detergent is indicated generally by the reference numeral 80.

15 The dispensing unit 80 has a fresh water inlet 81 which takes the form of a funnel 82 in register with a discharge conduit 83. In compliance with sanitation requirements, an anti-backup gap or break is provided in the line between the conduit 83 and the funnel 82. It will be understood that the conduit 83 is connected to a suitable source of domestic supply, whereby hot and cold water may be fed through the dispensing unit 80.

20 25 30 Although the construction of the dispensing unit 80, per se, does not form a part of the present invention, it may be noted that the mechanism within the interior thereof may include a double head piston valve disposed for axial movement within a measuring chamber enclosed within the cylindrical housing 84 and axially movable by a pivoted lever mechanism identified at 86.

35 The interior of the dispensing unit 80 further includes a two-way valve which controls communication of the outlet 79 with the mixing chamber inside of the housing 40 45 84 and which also controls the communication of the reservoir 78 with the mixing chamber. That valve is connected to an actuator 87 regulated by an electric solenoid motor 88. It will be understood that the flow of water through the conduit 83 can also be controlled 45 by an electrically operated valve indicated at 89.

45 Briefly described, the operation of the dispensing unit is as follows. The leverage mechanism 86 is adjusted to vary selectively the volume of the mixing chamber whereupon the solenoid motor 88 is energized to admit detergent from the reservoir 78 into the measuring chamber. The solenoid motor 89 is deenergized to close the conduit 83 and cut off the supply of water through the inlet funnel 82.

50 55 Upon deenergization of the solenoid motor 88, the detergent hopper 78 is closed and the outlet 79 is placed in communication with the measuring chamber. Energization of the solenoid motor 89 permits the flow of inlet water through the dispensing unit whereupon the supply of water will flush the detergent out of the 60 measuring chamber and into the washing compartment 24 through the outlet 79.

60 In the preferred embodiment herein illustrated, the inlet conduit 83 is connected to a heater tank 89 which is provided to insure an adequate supply of heated 65 washing and rinsing fluid.

65 70 75 In accordance with the principles of the present invention, sequential control means are provided for automatically operating the machine through a series of washing and rinsing periods. Thus, it will be apparent to those versed in the art that all of the electrically operated control devices including the electrically operated valves 61, 66, 70 and 89 as well as the electrically operated motors 48, 56 and 88 may be selectively energized for predetermined periods of time and in accordance with presetable control cycles. Thus, a program

schedule is obtainable whereby various combinations of spray patterns can be provided. It is desirable, for example, to operate the lower reaction spray arms 62 and 67 while the upper manifold sprays 73 and 74 are shut off and vice versa. Furthermore, optimum washability is obtained when the top and bottom sprays are used alternately. Moreover, final rinsing in accordance with the principles of the present invention is best done with the top manifold sprays 73 and 74 so that any remaining residue will be washed downwardly towards the sump 43.

In normal operation, the door 30 is opened and the dish rack 34 is pulled outwardly of the compartment 24. The houseware may be placed in the dish rack 34 without scraping or without any preliminary conditioning. By presetting the sequential control means, water from the heater tank 89 is added to the sump 43.

With all of the ware in the dish rack 34 positioned in the washing compartment or treatment zone 24 and the door 30 in closed position, the hot water is directed in jet fashion on the dishware alternately from the top and bottom sprays, thereby washing solid materials down to the chamber 46. The solid materials are disposed of by the pump disposal unit 47 and filtered water is supplied by the pump 53 for recirculation through the washing compartment or treatment zone 24.

After this prerinse period, the disposal pump unit 47 drains the chamber 46 to completely dispose of all solids and waste water through the drain outlet 18.

Upon initiation of the main washing period, a suitable amount of detergent is added from the reservoir 78 by the dispensing unit 80. It will be understood that the soiled washing solution will be disposed of as described above by the combination pump disposal unit 47.

The drying system of the dishwasher 22 consists of an outlet 90 (Figures 1 and 3) from the compartment or treatment zone 24 at which a blower 91 is mounted to draw vapor-laden air from the washing compartment 24 and force it through a conduit indicated generally at 92 and back into the inlet 93 of the washing compartment or treatment zone 24.

More specifically, the conduit 92 may include a condenser unit indicated generally at 95 where moisture is removed and then delivered to a heat exchanger 94 where the temperature of the air is raised before being forced into the washing compartment or treatment zone 24 through the inlet 93.

It will be understood that the condenser 95 conveniently comprises a condenser-type heat exchanger wherein a small flow of cold water is effected through the conduit connections indicated at 96 and 97, respectively, (Figure 3). The coolant and condensate can be conveyed to the waste line by conventional plumbing means which are not specifically illustrated herein.

The heat exchanger 94 constitutes a hollow enclosure 98 in which is situated heating elements 99 to effect an exchange of thermal energy to the air passing through the enclosure 98.

Although separate electric motors 48 and 56 are disclosed herein, it will be appreciated that the pump 53 and the combination pump disposal unit 47 could be driven by a single motor taking the form of a reversible electric motor arranged to drive one of the components in one direction of rotation and the other component in the opposite direction. Suitable "one-way" clutches well known in the art could be applied so that each driven component would be driven during operation of the motor in a given direction.

By virtue of the arrangement described above, it will be appreciated that the machine of the present invention will afford improved washability regardless of how the ware is racked in the dish rack 34 and that the distribution of water over the surfaces of the ware will be independent of the deflection of the water such as is

frequently the case in machines utilizing more than one level of rack loading.

The embodiment of Figure 5 is generally similar to the dishwasher already described and, accordingly, like reference numerals are applied wherever possible. In this form of the invention, however, a rotatable reaction spray arm 62a is provided having a plurality of longitudinally spaced nozzles 63a arranged to direct jets of fluid generally upwardly through the washing compartment or treatment zone 24a.

A second reaction spray arm is indicated at 67a and has a plurality of longitudinally spaced nozzles 68a. The axes of rotation of the reaction spray arms 62a and 67a are spaced less than the total length and more than one-half the length of the reaction spray arms and, accordingly, the spray arms 62 and 67 are in overlapping relation. Moreover, the spray arms 62a and 67a are disposed in coplanar relation so that the respective oppositely extending arm portions of each spray arm cover a common center area. Accordingly, it is desirable that some form of synchronizing means be provided to mechanically synchronize the rotative movements of the spray arms 62a and 67a. For example, as shown in Figure 5, the spray arm 62a is provided with a bevel gear 100 and the spray arm 67a is provided with a bevel gear 101. Suitable pinion means such as are indicated at 102 interconnect the gears 100 and 101, thereby insuring synchronized movement of the spray arms 62a and 67a.

In Figure 8, the synchronizing means are illustrated as comprising a pair of pulleys 100a and 101a interconnected by an endless belt 102a.

Referring now specifically to Figures 5 and 10, it will be noted that there is provided a dish rack 104 which conveniently comprises a rubber-coated wire form means providing a lower rack wall having a flat center section 106 and two side sections indicated at 107 and 108, respectively. The side section 107 is corrugated to provide a plurality of closely spaced angularly inclined portions 109 each separated by a vertically extending shoulder 110.

The side section 108 also has a plurality of angularly inclined portions 111 respectively separated by vertically extending shoulder portions 112.

A plurality of wire loops 113 are mounted in upstanding vertical disposition in the section 107. It will be noted that each loop has an offset leg 114 abutting against an angularly inclined portion 109 and an upright leg 116 which lies generally superjacent a corresponding vertical shoulder 110. A plurality of loops 117 are assembled in the section 108 of the rack 104, however, the loops 117 are somewhat higher or longer than the loops 113. Each of the loops 117 also includes bottom leg portions 118 abutting against the angularly inclined portions 111 and upstanding legs 119 which are vertically positioned above the vertically disposed shoulder portions 112. The loops 113 and 117 can conveniently comprise generally U-shaped members having curved bight portions at the upper end thereof and generally parallel dependent legs, such as are indicated at 116 and 119.

The center section 106 is provided with a plurality of loops 120. All of the loops 113, 117 and 120 partition the rack area into a plurality of dish compartments. As shown in Figure 10, a portion of the center section 106 on the rack 104 has a mesh wall indicated at 121 forming a floor for an enclosure bounded by mesh side walls indicated at 122, thereby to form a silverware compartment in the rack.

The section indicated at 107 of the rack will accommodate all sizes of plates, saucers, and dessert dishes. It will be noted that the lowermost portion of each angularly inclined portion 109 is disposed towards the center of the rack 104. Accordingly, all of the dishes in the section 107 will face the center of the rack and will be supported at three point contact with the wires

of the wire form means, thereby facilitating removal of all food particles from the dishware.

The rack 104 is also provided with side wall portions indicated at 123 which encircle the rack area. Suitable roller means, as indicated at 124 are attached to the rack 104. The rollers 124 engage a track 35a carried by the end walls 26, 26 of the casing 23 and also engage the trackway surface 38 formed on opposite ends of the inner wall surface 39 of the door 39.

The section indicated at 106 on the rack 104 will accommodate all sizes of cups and glasses. These cup-shaped receptacles are supported at an angle to allow draining of the water or other liquid impinged thereupon and since they are located in the center section of the rack, it will be noted that they are superjacent the area of overlap indicated as lying between the points A, B (Figure 8). Thus, the cups and glasses will be washed by liquid from both spray arms 62a and 67a.

The section indicated at 108 will accommodate deep dishes as well as all other sizes of dishware. The lowermost portion of the inclined portions 111 are towards the center of the rack so that all of the dishes will have point contact with the wire form means and will face towards the center of the rack.

The silverware stacked in the silverware compartment will also be exposed to the double washing effect resulting from the overlap area A, B. This is particularly desirable because of the nesting effect which results upon placing a large amount of silverware on the mesh floor 121. Referring now to Figures 8, 11 and 12, it will be noted that each spray arm 62a and 67a provides a longitudinal row of nozzles. Thus, as seen in Figure 8, if the rotational axis of the spray arm 67a is considered to lie at C a plurality of nozzles 68a extend laterally from one side of the axis C corresponding to a side of the spray arm 67a indicated at D and a corresponding plurality of nozzles 68a extend laterally on the other side of the axis C on a side indicated at E.

According to the principles of the present invention, all of the nozzles 68a are tilted or angularly offset. Referring to Figure 11, however, it will be noted that the nozzles on the side E are offset an amount equal to the angle F, while the nozzles on the side D are offset by an amount equal to the angle G (Figure 12). It will be noted upon inspecting and comparing Figures 11 and 12 that the angles F and G are different, and angle G being greater than the angle F. In both instances, however, the offset is in the same direction. The difference between the angles F and G provides the reaction driving force vector, which reaction driving force results in the rotation of the spray arm 67a.

Furthermore, because all of the nozzles 67a in both sides D and E are offset in the same direction, an improved liquid distribution will be effected. For example, referring to the right upper hand side of Figure 8, a representative dish is indicated at H and it will be noted that this dish is hit by liquid on both the front and back sides. This is due to the fact that the nozzles or orifices 68a are disposed on the same side of the spray arm 67a and as can be seen from the solid and dotted line positions of the arm, one extension such as the side D sprays one side of the dish H, while the other extension such as the side E sprays the other side of the dish.

If it is desired to simultaneously pivotally oscillate the reaction spray arms while rotating the same, the embodiment of the invention illustrated in Figures 6 and 7 may be employed. For example, a dishwasher is indicated at 150 and provides a treatment zone 151 in which is positioned a dish rack 152 superjacent one or more reaction spray arms 153. Water is supplied to the reaction spray arm 153 by a pump indicated schematically at P. The pump outlet is connected to a mounting tube 154 having bearing means 156 on the end thereof and discharging a moving stream of liquid at increased pressure and velocity into the hollow interior 157 of a motor

casing 158 rotatably mounted on the bearing means 156. A suitable bearing means 159 is shown formed on the motor casing 158 to cooperate with the bearing means 156 and there is further provided an orifice 160 through

5 which the fluid is discharged from the mounting tube 154. A reaction wheel 161 carried on a shaft 162 and journaled within the motor casing 158 is rotatably driven by the fluid stream impinging thereupon. A worm 163 connected to the shaft 162 drives a reduction gear 164 carried by a shaft 166 which is also journaled in the motor casing 158. The shaft 166 carries a worm 167 which engages a gear 168 attached to a shaft 169 journaled in the motor casing 158 and extending outwardly thereof. A crank arm 170 is connected on the end of the shaft 169 by means of fasteners indicated at 171. A link member 172 fastened to the reaction spray arm 153 is pivotally connected as at 173 to the crank arm 170. Thus, rotation of the reaction wheel 161 effects a mechanical driving of the crank arm 170 and an oscillation of the tube 153. The oscillation of the reaction spray arm 153 is illustrated in Figure 6 and is indicated by the angles 174 and 176. It will be noted that the angle 176 is greater than the angle 174 so that the displacement and dwell of the oscillating spray arm 153 is greater on one side than on the other. In other words, the nozzles are offset in appropriate direction with respect to opposite sides of the rotational axis determined by the bearing means 156 and 159 so that the reaction from the nozzles indicated at N₁ and N₂ on opposite sides 20 of the spray arm 153 will rotate not only the spray arm 153 but also the motor casing 158. Consequently, the spray arms 153 will oscillate back and forth and will also be rotated to give a constantly changing pattern of liquid distribution.

25 35 It may be noted that the spray arm 153 is pivotally carried as at 175 by the motor box 158 and that the spray pattern indicated in Figure 6 is diagrammatically illustrated only for purposes of illustration and depicts the spray arm 153 rotated through 90° so that the degree 40 of pivotal oscillation may be conveniently illustrated.

In Figure 9 is shown an actual structural embodiment of a dishwasher incorporating the principles of the present invention and specifically embodying a two-way valve operated by an electric solenoid and operable to alternate 45 the top and bottom spray means. Thus, there is provided a pump 53b driven by a motor 56b and liquid discharged by the pump 53b is delivered to an outlet conduit 57b. Flow from the outlet conduit 57b to a branch conduit 58b leading to one of the reaction spray arms, 59b leading to the second reaction spray arm and 60b leading to the upper spray manifolds is controlled by a two-way valve indicated generally by the reference character V. As noted on Figure 9, the valve V has a single inlet I connected to the conduit 57b and two outlets, 55 outlet O₁ being connected to the conduits 58b and 59b leading to the reaction spray arms and O₂ being connected to the conduit 60b leading to the upper spray manifolds.

The valve V is of the solenoid operated type so that 60 flow from the conduit 57b may be alternately shifted between outlets O₁ and O₂. In this connection, the movable portion of the valve V is indicated at 250 connected through a coil spring 251 to the plunger 252 to a solenoid motor including a coil 253. The solenoid is mounted 65 on a bracket 254 attached to the valve V by a plurality of fasteners indicated at F.

70 It will be understood that the solenoid 253 is electrically connected to the circuitry controlled by the sequential control means of the dishwasher so that the alternate top and bottom spraying of the dishware may be effected in accordance with the programing schedule preset by the operator of the machine.

75 Although various minor structural modifications might be suggested by those versed in the art, it should be understood that we wish to embody within the scope of the

patent warranted hereon all such modifications as reasonably and properly come within the scope of our contribution to the art.

We claim as our invention:

1. A dishwasher comprising means forming a generally rectangular washing compartment having rear, side, top and bottom walls and a front opening, a hinged door for closing said front opening movable from a closed position into a generally horizontally disposed open position, reaction spray arm means in the bottom of said compartment directing jets of fluid in a path extending upwardly throughout said compartment, support means carrying said spray arm means for rotation including pivot means between said support means and said spray arm means, a pair of spray manifolds extending between said end walls at the front and rear edges of said top wall for directing jets of fluid in a path extending downwardly through said compartment, a basket movable into and out of the path of said liquid jets in said compartment, a delivery pump having conduit means connected to said spray arm means and to said spray manifold form a source of liquid, and motor means having a driving connection with said spray arm means to pivotally oscillate said spray arm means for moving the upwardly directed liquid jets in a changing pattern throughout said basket positioned in the path of said liquid jets in said compartment, said conduit means including valves to selectively project jets of liquid from said spray arm means and said manifolds in predetermined spray patterns.

2. A dishwasher as defined in claim 1, and presettable sequential control means in control of said valves for automatically operating said machine through a series of washing and rinsing periods to alternately project jets of fluid from said spray arm means and said manifolds.

3. A dishwasher comprising means forming a generally rectangular washing compartment having rear, side, top, bottom and front walls, reaction spray arm means in the bottom of said compartment directing jets of fluid generally upwardly, support means carrying said spray arm means for rotation including pivot means between said support means and said spray arm means, a pair of spray manifolds extending between said end walls at the front and rear edges of said top wall for directing jets of fluid generally downwardly and motor means having a driving connection with said spray arm means to pivotally oscillate said spray arm means concurrently with rotation thereof, thereby to move said upwardly directed jets of fluid in a changing pattern throughout said washing compartment.

4. A dishwasher comprising means forming a generally rectangular washing compartment having rear, side, top and bottom walls and a front opening, a hinged door for closing said front opening movable from a closed position into a generally horizontally disposed open position, reaction spray arm means in the bottom of said compartment directing jets of fluid in a path extending upwardly throughout said compartment, support means carrying said spray arm means for rotation including pivot means between said support means and said spray arm means, a pair of spray manifolds extending between said end walls at the front and rear edges of said top wall for directing jets of fluid in a path extending downwardly through said compartment, a basket movable into and out of the path of said liquid jets in said compartment, a delivery pump having conduit means connected to said spray arm means and to said spray manifold from a source of liquid, and motor means having a driving connection with said spray arm means to pivotally oscillate said spray arm means for moving the upwardly directed liquid jets in a changing pattern throughout said basket positioned in the path of said liquid jets in said compartment.

5. A dishwasher comprising means forming a generally rectangular washing compartment having rear, side, top, bottom and front walls, a mounting tube in the bottom of said compartment having bearing means on the end there-

of and discharging a moving stream of liquid at increased pressure and velocity, a motor casing rotatably mounted on said bearing means in said compartment, a reaction wheel journaled in said casing and rotatably driven by 5 said moving stream of liquid, a crank arm linkage having a driven connection with said reaction wheel, a reaction spray arm pivotally carried by said motor casing having a longitudinal row of nozzles extending from opposite sides of the axis of rotation of said motor means, 10 means operatively connecting said spray arm to said linkage to pivotally oscillate said spray arm through a displacement and dwell greater on one side than on the other, the effective angular placement of said nozzles on opposite sides of said axis being relatively offset a sufficient 15 amount to produce a reactive force for rotating said spray arm and said motor casing, and means supplying fluid under pressure to said reaction spray arm to direct jets of fluid generally upwardly in a changing pattern throughout said washing compartment.

20 6. In a dishwasher, means forming a generally rectangular treatment zone, a dish rack in said zone for holding dishware and a pair of rotatable reaction spray arms below said rack having rows of nozzles for projecting jets of liquid through the treatment zone, each said 25 spray arm comprising support means carrying said spray arm for rotation and including pivot means between said support means and said arm, motor means, and means operatively connecting said motor means to said pivot means to pivotally oscillate said spray arm through a displacement and dwell greater on one side than on the other, the effective angular placement of said nozzles on opposite sides of said axis being relatively offset a sufficient 30 amount to produce a reactive force for rotating said spray arm concurrently with the oscillation thereof, said 35 treatment zone having a sump formed at the bottom thereof, a combination drain pump and disposal unit in communication with said sump and taking suction thereon, said unit including an outlet means having a filter screen therein, a delivery pump having conduit means 40 connected to said outlet means arranged to conduct filtered liquid to said spray arm, and a waste pipe conduit connected to said unit to receive and discharge residue to drain.

45 7. A dishwasher comprising means forming a generally rectangular washing compartment having rear, side, top, bottom and front walls, reaction spray arm means in the bottom of said compartment directing jets of fluid generally upwardly, and a pair of spray manifolds extending between said end walls at the front and rear 50 edges of said top wall for directing jets of fluid generally downwardly, said compartment having a sump formed at the bottom thereof, a combination drain pump and disposal unit in communication with said sump and taking suction thereon, said unit including an outlet means having a filter screen therein, a delivery pump having conduit means connected to said outlet means arranged to conduct filtered liquid to said spray arms and said manifolds, and a waste pipe conduit connected to said unit to receive and discharge residue to drain.
